(74) Attorney, Agent, or Firm — JEEN IP LAW, LLC

(57) **CLAIM**

The ornamental design for a duster, as shown and described.

DESCRIPTION

FIG. 1 is a front, right and bottom perspective view of a duster, showing my new design;

FIG. 2 is a rear, left and bottom perspective view thereof;

FIG. 3 is a perspective view thereof shown in folded thereof;

FIG. 4 is a perspective view thereof shown in storage thereof;

FIG. 5 is a front view thereof;

FIG. 6 is a rear view thereof;

FIG. 7 is a left side view thereof;

FIG. 8 is a right side view thereof;

FIG. 9 is an enlarged top plan view thereof;

FIG. 10 is an enlarged bottom plan view thereof;

FIG. 11 is an enlarged view of area "11" in FIG. 1; and,

FIG. 12 is an enlarged view of area "12" in FIG. 2.

The even-dashed broken lines in FIG. 4 depict portions of the duster that form no part of the claimed design. The dot-dash broken lines in FIGS. 1-2 and 11-12 depict boundaries of the enlargement indications and form no part of the claimed design.

1 Claim, 12 Drawing Sheets
